UNITED STATES PATENT OFFICE.

ERIK A. COLLIN, OF TURNER, NEBRASKA.

CHURN.

No. 878,938.

Specification of Letters Patent.

Patented Feb. 11, 1908.

Application filed May 13, 1907. Serial No. 373,396.

To all whom it may concern:

Be it known that I, ERIK A. COLLIN, a citizen of the United States, residing at Turner, in the county of Holt and State of Nebraska, have invented certain new and useful Improvements in Churns, of which the following is a specification.

This invention pertains to churning and operating mechanism therefor, of the type designed particularly for home use and comprising a churn body or receptacle which is revolved or rotated relative to suitable paddles received therein, said paddles being stationary throughout a churning operation, and the parts being assembled in a substantial and desirable manner to facilitate operation.

The invention embodies particularly, peculiar and novel structural features which will be more fully described hereinafter and which will be finally claimed.

For a full understanding of the invention and the merits thereof and also to acquire a knowledge of the details of construction of the means for effecting the result, reference is to be had to the following description and accompanying drawings, in which:

Figure 1 is a side elevation of a churn embodying the invention; Fig. 2 is a vertical longitudinal sectional view bringing out clearly the arrangement of the several parts of the mechanism, and Fig. 3 is a top plan view, the cover of the churn being removed.

Corresponding and like parts are referred to in the following description and indicated in all the views of the drawings by the same reference characters.

Specifically describing the invention, and referring to the drawing, the numeral 1 indicates a stand which may be of any suitable construction and which preferably comprises supporting legs 2. Attached substantially to the top of the stand 1 are spaced pillow blocks 3 in which is journaled a horizontal shaft 4. A small pinion 5 is secured to one end of the shaft 4 and is in mesh with a gear 6 carried by a shaft 7 journaled in any desired manner in the upper end portions of spaced supporting members 8 which project upwardly from one end of the stand 1 from an end of the latter. A crank handle 9 is attached to one end of the shaft 7 and is operated in order to turn the gear 6 and the shaft 4, connected therewith. The end of the shaft 4 opposite that carrying the pinion 5 has a bevel gear 10 attached thereto and said bevel pinion is in mesh with a similar

pinion 11, horizontally arranged and journaled upon a stem 12 which projects upwardly from the stand 1 near the gear 10. At the lower end of the stem 12 and surrounding the same is a cup 13 in which are received a suitable number of ball bearings, the lower hub portion of the gear 11 being received in the cup 13 and being in contact with the ball bearings designated 14 located inside of the cup. In other words the gear 11 is supported on the ball bearings 14 and rotates freely in mesh with the gear 10.

The body 15 of the churn consists of a suitable receptacle, and is also journaled for rotation upon the stem 12. Said churn body is provided with a tubular extension 16 located centrally of the bottom thereof, the tubular portion of said extension being coincident with an opening at the center of the churn body 15. The under side of the churn body 15 is formed with downwardly extending projections or lugs 17 at opposite sides of the opening therein and said lugs enter depressions or recesses 18 in the upper side 80 of the gear element 11 and an interlocking connection is thus established between the gear element 11 and the churn body, whereby when the gear 11 is rotated the churn body will revolve therewith. The extension 85 16 of the churn body 15 terminates at its upper end in the plane of the upper end of the churn body so that the liquid which is to be operated upon may fill the churn nearly to the top thereof. The stem 12 projects 90 some distance above the extremity of the tubular extension 16 and received on the projecting portion of the stem is a collar 19. Said collar 19 is provided with opposite horizontal threaded openings leading to the 95 vertical opening which receives the stem 12 and in said threaded openings are received the threaded members 20. The members 20 have the inner ends thereof adapted to engage with the stem 12 in order to positively 100 attach the collar 19 thereto, and each of the members 20 is formed with an opening leading from its outer extremity and threaded so as to receive the threaded extremity of a lateral arm 21 projecting from the upper portion of a paddle 22. In other words the members 20 not only attach the collar 19 to the stem 12 but they also constitute supporting members for the paddles 22 which are attached thereto in the manner above 105 described. Said members 20 thus perform a specific dual function. If necessary the

paddles 22 may be vertically adjusted by vertical adjustment of the collar 19. Each of the members 20 is formed at its outer end with a hub to admit of ready application of 5 a wrench or similar tool for adjusting the member in the manner specified.

The suitable cover 23 is provided for the receptacle of churn body 15 and said cover receives the upper portion of the churn body 10 when the parts are in operative positions. The cover 23 is formed with a central opening through which the upper extremity of the stem 12 passes, said cover being thereby centered.

15 It is contemplated that the various shaft and gear elements of the churn shaft be mounted in ball bearings, if desired, in order to facilitate the free revolution of the parts, and increase the ease of operation of the 20 machine.

The paddles 22, being constructed with an irregular or angular contour, have a peculiar function of breaking up the cream, and also tend to prevent the cream from riding up the 25 wall of the churn body by reason of centrifugal force.

Having thus described the invention what is claimed as new is:—

1. In churn operating mechanism of the 30 class described, and in combination, a stand, a horizontal shaft journaled upon said stand, a pinion at one end of the shaft, an operating gear in mesh with said pinion, a bevel pinion at the opposite end of said shaft, a vertical 35 stem projecting upwardly from the stand adjacent to said bevel pinion, a cup located at the lower end of said stem and surrounding the latter, ball bearings received in said cup, a horizontal bevel pinion journaled upon 40 the stem and having its lower hub portion resting upon the ball bearings aforesaid, a churn body having a centrally upwardly projecting tubular extension at its central portion and through which the stem above mentioned passes, whereby the churn body is 45 supported for revolution on the stem, the bottom of the churn body being formed with an opening coincident with the tubular area of the extension aforesaid, lugs projecting 50 from the bottom of the churn body on opposite sides of the opening therein, the top of the horizontal bevel pinion aforesaid being formed with recesses receiving the lugs and establishing a detachable interlocking con-

nection between the churn body and said 55 pinion, a collar applied to the upper end portion of the stem, paddles attached to said collar and about which the churn body is adapted to rotate, and a cover for the upper end of the churn body.

2. In churn operating mechanism of the 60 class described, and in combination, a stand, a horizontal shaft journaled upon said stand, a pinion at one end of the shaft, an operating gear in mesh with said pinion, a bevel pinion 65 at the opposite end of said shaft, a vertical stem projecting upwardly from the stand adjacent to said bevel pinion, a cup located at the lower end of said stem and surrounding the latter, ball bearings received in said cup, a horizontal bevel pinion journaled upon 70 the stem and having its lower hub portion resting upon the ball bearings aforesaid, a churn body having a centrally upwardly projecting tubular extension at its central portion and through which the stem above 75 mentioned passes, whereby the churn body is supported for revolution on the stem, the bottom of the churn body being formed with an opening coincident with the tubular area 80 of the extension aforesaid, lugs projecting from the bottom of the churn body on opposite sides of the opening therein, the top of the horizontal bevel pinion aforesaid being formed with recesses receiving the lugs and 85 establishing a detachable interlocking connection between the churn body and said pinion, the upper end portion of the stem projecting some distance above the upper extremity of the tubular extension, a collar 90 disposed upon and receiving the upper extremity of the stem, horizontally threaded members screwed into said collar and adapted to engage the stem to fix the position of the collar thereon, said threaded members 95 being provided with internal threaded openings, paddles arranged in the churn body and having lateral arms at the upper ends thereof formed with threaded extremities received in the threaded openings of the threaded members applied to the collar, and a cover for the 100 churn body.

In testimony whereof I affix my signature in presence of two witnesses.

ERIK A. COLLIN.
